UNITED STATES PATENT OFFICE.

HOWARD HARSH, OF OSAKIS, MINNESOTA.

FOLDABLE CRATE.

1,325,323.

Specification of Letters Patent. Patented Dec. 16, 1919.

Application filed May 2, 1919. Serial No. 294,312.

To all whom it may concern:

Be it known that I, HOWARD HARSH, a citizen of the United States, residing at Osakis, in the county of Douglas and State 5 of Minnesota, have invented a new and useful Foldable Crate, of which the following is a specification.

This invention relates to improvements in crates, the primary object of the invention 10 being to provide a collapsible or foldable crate that is self-contained, that is to say, one in which all the parts are so connected together that it is impossible to accidentally separate them, and therefore the liability of 15 loss of any of the parts of the crate is entirely eliminated.

A further object of the invention is to provide a crate of this character in which the various elements are so constructed as to 20 coöperate in locking the crate in both open or operative and closed or knocked-down condition, and which is simple in construction, inexpensive to manufacture, and extremely practical and durable in use.

25 With these and other objects in view, which will appear as the description proceeds, my invention resides in the various novel features of construction and combination of parts as will be clearly understood 30 from the following description and finally pointed out in the claims.

In the drawings accompanying and forming part of this specification,

35 Figure 1 is a perspective view of my improved crate, with parts broken away to better show certain features of construction; and

Fig. 2 is a longitudinal section of the crate locked in its operative or upright position.

40 The same characters of reference designate the same parts in the different figures of the drawings.

In the embodiment of the invention herein illustrated, 2 designates a bottom, which is 45 preferably, although not necessarily, made solid and which has secured thereto around its sides and ends a base board 3. To the bottom 2, within said base board are hingedly secured a pair of side walls 4 and end 50 walls 5 and 6, these side and end walls being formed of horizontal slats connected together by vertical brackets in the usual manner. Each of the end walls is provided at each end thereof with a corner post 7. 55 The side walls 4 are provided at their upper ends with angle members 8, which project

over the ends of the end walls 5 and 6 and assist in preventing such end walls from falling outward when the walls are swung upward into open or operative position. 60 At the longitudinal center of the bottom 2 I provide a partition 9, which is hinged to the bottom and is adapted to abut against the center brackets of the side walls 4 when the partition is in upright position. In order 65 to retain the partition in its upright position, I have provided wires 10 which are connected at one end to the top of the end wall 5 and at the other end to the top of the partition, in such manner that when the end 70 wall is raised to upright position it will also raise the partition 9 and when the partition is folded down it will carry the end wall 5 down also.

To the outer edge of each of the side walls 75 4 is attached by means of hinges 11 a top or cover member 12 and 13 respectively, these cover members being made up of longitudinal slats connected by brackets in a manner similar to the side walls. These 80 cover members are adapted to overlap approximately at the middle of the width of the crate, and for this purpose the brackets of one of the cover members are placed in staggered relation to or out of alignment 85 with those of the other. The lengthwise slats of the cover member 12 are omitted at the place where it is overlapped by the member 13, said member 13 also having a space within the overlapping area in which the 90 lengthwise slats are omitted, as clearly shown in Fig. 1, for a purpose presently to be described. The crosswise extending slats or brackets at the ends of the cover member 13 are cut out or recessed, as shown at 14, so 95 that when this cover member is in operative position the corner posts at one end of each of the end walls project into these recesses and are thus maintained in upright position 100 between said brackets and the angle members 8. The post at the opposite end of each of the end walls projects into and is held in a similar manner by a recess 14 formed in each of the end brackets of the cover member 12, all as clearly shown in Fig. 1. 105

The overlapping of the cover members 12 and 13 is for the purpose of locking the crate in upright or operative position and at the same time retaining the cover securely fastened against accidental opening. This 110 is accomplished by the provision of a metal strap 16 secured at the outer end of each of

the end brackets of the cover member 12, the end brackets of the cover member 13 being recessed or cut away as shown at 17 for permitting these straps to project up 5 through said brackets. A similar strap 18 is provided on the upper side of the center bracket of the cover member 13 in alinement with the straps 16 when the cover members are in overlapping position, whereby when 10 in such position a locking board 19 may be slid through such straps, thus filling the space left without slats in the overlapping covers and retaining the cover members securely locked together and making the col- 15 lage of the crate impossible. For the purpose of locking the crate in its knocked-down condition, I have provided at each end of the cover member 13 a spring-pressed locking bolt 20 secured to the end brackets 20 between the slats. Any suitable form of spring-pressed bolt may be used for this purpose, and the base board at each end of the crate has a hole bored therein which will be in alinement with the bolt when the 25 crate is in folded position so that on pressing down the cover member the bolt will be shot into the openings and thereby lock the crate in its folded condition.

When it is desired to collapse or fold the 30 crate, the locking board 19 is removed and the cover members lifted. The end wall 5 is then pushed inwardly and, owing to its wire connection with the center partition, carries the latter down with it. The oppo- 35 site end wall 6 is then folded inwardly, after which the side wall carrying the cover mem- 40 ber 12 is folded inwardly, the board 19 having been passed through the straps 16 so as to be retained thereby. Lastly, the opposite side wall carrying the cover member 13 is 45 folded down into the base board, the spring-pressed bolts carried thereby projecting into the holes in the base board and securely locking the crate in its knocked-down condition.

From the foregoing it will be seen that I 50 have provided a crate which is practically a unitary structure, the parts being so connected that loss is impossible, the members coöperating to securely lock the crate in its upright position, and which when locked in its knocked-down condition is very small and compact, thereby occupying but little storage space and producing a crate which is easy to handle and adapted to be quickly 55 set up for use.

Having thus described my invention, what I claim is:

1. A foldable crate, comprising a bottom, side and end walls hinged to said bottom, a dividing partition hinged to said bottom, 60 means connecting said partition with one of said end walls whereby said end wall and partition are swung in unison, a pair of overlapping covers one hinged to each of said side walls, means carried by said covers for retaining said end walls in upright position, and coöperating means also carried by said covers for locking the same in covering position.

2. A foldable crate, comprising a bottom, 70 side and end walls hinged to said bottom, said end walls being provided with corner posts, a pair of overlapping covers one hinged to each of said side walls, said covers being provided with recesses for receiving 75 the upper ends of said corner posts when in upright position, and coöperating means carried by said covers for locking the same in overlapping position.

3. A foldable crate, comprising a bottom, 80 side and end walls hinged to said bottom, said end walls being provided with corner posts, a pair of overlapping covers one hinged to each of said side walls, said covers being provided with recesses for receiving 85 the upper ends of said corner posts when in upright position, the overlapping portions of said covers being provided with alined guides for retaining a member in position for locking said covers in overlapped rela- 90 tion.

4. A foldable crate, comprising a bottom provided with a base board extending there-around, side and end walls hinged to said bottom, a dividing partition hinged to said bottom, means connecting the dividing partition and one of the end walls for holding the partition and end wall in elevated and spaced relation, a pair of covers one hinged to each of said side walls, all of said hinged members being adapted to be folded on said bottom within said base board. 95

In testimony that I claim the foregoing as my own I have hereto affixed my signature in the presence of two witnesses.

HOWARD HARSH.
